X-RAY APPARATUS

Ernest E. Charlton and Willem F. Westendorp,
Schenectady, N. Y., assignors to General Electric Company, a corporation of New York

Application December 2, 1936, Serial No. 113,862

14 Claims. (Cl. 250—87)

The present invention relates to electrical discharge apparatus such as high voltage X-ray equipment.

It is an object of the invention to provide a shock-proof, semi-portable X-ray equipment which is adapted both for medical and industrial applications and which may be safely operated at potentials at least as great as 500,000 volts. Particular features of the invention which contribute to this result are an improved arrangement of the X-ray tube with respect to its energizing means, novel means for preventing electrical breakdown between the various parts of the equipment, and special provisions for safely regulating the cathode temperature and the output of the tube. In a preferred embodiment, the equipment as a whole comprises an oil-filled casing enclosing a high voltage transformer and the cathode end of an X-ray tube, the anode end of the tube being arranged to project externally of the casing wall.

The novel features which are considered to be characteristic of the invention are pointed out with particularity in the appended claims. The invention itself, together with further objects and advantages thereof may best be understood by reference to the following description taken in connection with the drawings in which Fig. 1 is a sectional view of a complete apparatus suitably embodying the invention; Fig. 2 is a partial plan view of the structure of Fig. 1 showing certain of the upper elements removed; Fig. 3 is a fragmentary view showing in detail the construction of the X-ray tube cathode indicated more generally in Fig. 1; Figs. 4, 5 and 6 illustrate the details of the X-ray tube anode and the tube mounting; Fig. 7 is a composite section taken along line 7—7 of Fig. 2 and showing the construction and arrangement of the energizing means, and Fig. 8 illustrates schematically preferred circuit connections for the apparatus.

Referring particularly to Fig. 1 there is shown an X-ray apparatus enclosed in a casing or tank 10 which is preferably of fabricated construction and is so assembled as to be essentially vacuum-tight. The form of the tank illustrated is such as to permit the minimum volume consistent with the requirement of maintaining adequate spacing between the various enclosed high potential elements.

The casing is filled during operation with a dielectric medium, for example, insulating oil or an insulating gas. To permit the ready introduction and removal of such a medium, the casing is provided at its highest point with a conduit 12

which may lead to an expansion tank and at its lowest point with a drainage valve 13. Since it is contemplated that the apparatus as a whole may be rotatable about one or more axes and to a certain extent portable, the casing may be provided with suitable mounting means consisting in part of a trunnion support indicated in Fig. 2 by the numeral 14 and preferably located on a line passing through the center of gravity of the apparatus. 10

Within the casing, there is provided energizing means comprising a transformer which includes a laminated core 16 set into cooperating recesses formed in the tank walls. A primary winding, suitably consisting of a single helical layer of copper ribbon 18, is wound on one leg of the transformer core, and an insulating sleeve 19 consisting for example, of paper impregnated with shellac, is interposed between this winding and the laminations of the core. Connections to an external source of power may be made by means of insulated conducting straps 22 and 23 to whose ends there may be connected lead-in conductors sealed through the wall of the casing. 15

In the arrangement illustrated, the transformer secondary comprises an elongated coil 26 having one end adjacent to and partially supported by the lower casing wall 27 to which it may also be electrically connected. Such a connection is preferably made indirectly through a current meter, for example, by means of a conductor 28 brought out through the wall of the casing. 20

The upper end of the secondary coil 26 is appreciably spaced from the casing and is adapted to be maintained at a high potential with respect to the casing and the various metal parts connected therewith. In the use contemplated the potential developed across the secondary coil 26 may be in excess of 500,000 volts so that considerable electrostatic stress will exist between the upper turns of the coil and the apparatus parts which are at casing potential. In order to reduce this stress and to increase the uniformity of the electrostatic field existing in the casing, there is provided in connection with the upper end of the coil an electrostatic shield in the form of a hollow conducting body 30 having a relatively large radius of curvature. This body may suitably comprise separable upper and lower metal parts and is adapted to enclose various operative parts of the apparatus within its confines. 40

The structure so far described constitutes means for energizing an X-ray tube or a simi- 55

5   lar electrical discharge device. We have illustrated a particular device as comprising an elongated envelope consisting at least in part of vitreous insulating material and provided at its opposite ends with terminals connecting with enclosed discharge electrodes. More specifically, the tube envelope consists of spaced insulating sections 35, for example, of glass, and interposed metal sections 36 sealed thereto. At the end of 10   the envelope which projects toward the interior of the casing 10, there is provided a cathode including a separately heated filament 37 and a focusing cup 38, these members to be described more fully hereinafter. Arranged at the other 15   end of the tube, there is an anode consisting of an elongated metal cylinder 40, while between these main discharge electrodes, there are arranged a plurality of evenly spaced intermediate electrodes 41. These latter electrodes preferably 20   comprise longitudinally extending tubular conducting members. They are supported by and connected to conductive envelope portions 36 which thus constitute exposed terminals for the enclosed electrodes.

25 In accordance with the invention, the X-ray tube is arranged so that its major axis is transverse to and preferably perpendicular to the axis of the transformer coil 26, the cathode end of the tube being adjacent the upper end of the coil
30 while the anode end of the tube projects through and is supported by the casing wall 42. In order to insure uniform distribution of potential along the length of the X-ray tube envelope connections are made between the spaced electrodes 41
35 and correspondingly spaced points along the length of the transformer coil 26. The angular relationship existing between the tube and the axis of the coil permits these connections to be made in a manner which creates no danger of electrical breakdown regardless of any difference in length which may exist between individual tube and coil sections. Additional safety in this respect may be obtained by forming the connecting members 45 as conducting tubes or rods of relatively large diameter as indicated. It may further be desirable to incorporate high resistance sections 46 in the members 45, such sections being useful in limiting the current which is able to flow in case of a disruptive breakdown with the X-ray tube.

50 Inasmuch as in operation the successive intermediate electrodes are energized at progressively higher potentials with respect to the casing, strong radial fields exist between these electrodes
55 and the casing walls. Due to the relatively small radius of curvature of the electrodes and the disparity between the dielectric constant of the vacuum within the envelope and the oil or other dielectric medium outside, extremely high potential
60 gradients may be established adjacent the electrode surfaces. With operating potentials of the magnitude contemplated, these gradients may, in the absence of protective measures, be sufficient to produce "cold cathode discharges" in a radial direction and to cause puncturing of the envelope walls.
65

In order to prevent such occurrences, our invention provides electrostatic shielding means in connection with at least those electrodes which are nearest to cathode potential. Such means may comprise, for example, tubular members 47 of relatively large radius of curvature electrically connected to selected ones or all of the high potential electrodes. As illustrated, each of these members is formed so as to present no sharp edges

and is positioned between its corresponding intermediate electrode and the wall of the casing. As a result of the favorable shape of the members 47 and their disposition in the dielectric medium outside the discharge envelope, high local gradients are avoided and the danger of disruptive discharges precluded.

The various shielding members are mechanically supported by means of an insulating cylinder 48 consisting, for example, of paper impregnated with shellac. This cylinder is positioned between the envelope and the shielding members and may be secured at least against rotary motion by means of a keying connection (not shown) with the hollow conducting body 15 30. Connections between the shielding members and the electrode terminals 36 may be effected by means of spring-pressed slidable contacts whose nature and function will be more fully explained hereinafter. 20

The details of the tube construction and particularly of the anode construction will be more readily apparent upon reference to Fig. 4. In this figure, the anode is shown as comprising an elongated metal tube 40 terminating at its left-hand extremity in a relatively heavy metal plate 49 inclined to the main axis of the tube. This plate is provided centrally with a target surface 50 comprising an insert of metal, for example, tungsten. During operation the stream of electrons proceeding from the cathode may be focused to converge on the target 50 by means of a magnetic coil 52 arranged so that its axis coincides with that of the tube and excited in any desired manner. The plate 49 is maintained at a temperature below the melting point of the target surface by circulating water or an equivalent cooling fluid in contact with its outer face. A particular means for accomplishing such circulation is illustrated as comprising an inlet tube 51 wound helically around the anode throughout its length and terminating in a series of labyrinthine chambers on the outer surface of the plate 49. From these chambers the cooling fluid is permitted to escape through an opening 43 into the annular space between the anode tube 40 and a surrounding shell 54. From here it may be finally drawn off through an outlet connection 56 (Fig. 5).

The escape of X-rays in any other than a chosen direction is substantially prevented by the use of a sheath 57, suitably of lead. This sheath, which is covered externally with a smooth metal casing 64, is of greatest thickness in the region closely adjacent the target surface and diminishes in thickness as one proceeds toward the apparatus casing. Provision is made for the escape of X-rays in the desired direction through a window which is closed only by a thin metal section 58. In order to permit variation of the direction of the X-ray beam, the tube structure as a whole may be rotatably mounted with respect to the casing 10, an exemplary such mounting being illustrated in Fig. 4. Essentially the structure shown comprises cooperating bearing surfaces 59 having interposed between them suitable oiltight packing means 60. The movable element of this bearing combination is connected to a gear wheel 61 which in turn supports the tube structure as a whole through the intermediation of a flange 70 62. The gear wheel 61 may be driven to produce a desired rotation of the tube by means of a worm gear 63.

In order that rotation of the tube may not interfere with the electrical connections between

the intermediate electrodes 41 and the transformer coil 26, these connections may include the slideable spring-pressed contacts 65 riding on the outer surfaces of the metal envelope parts 36 as best shown in Fig. 6. The conductors 45 are secured to the stationary shielding members so that no relative motion takes place between them. The cathode connections may readily be given sufficient flexibility so that no special provisions need be made to permit of their rotation.

The cathode itself, which is shown in detail in Fig. 3, comprises a separately heated filament 37 and a focusing cup 38, of metal or other conducting material. Insulated lead-in conductors 68 and 69 are provided for the filament while a similar conductor 70 is attached to an externally exposed portion of the focusing cup. Heating current for the filament is derived from a secondary coil 71 comprising a few turns of wire wound about the insulating ring 32 and constituting in effect an extension of the main secondary coil 26 (Figs. 1 and 7).

The cathode end of the X-ray tube is positioned near the high potential end of the secondary coil 26 in such a way that the cathode as well as all its external connections are enclosed within the hollow conducting member 30. Since the enclosure comprises essentially a field-free space it is unnecessary to take any precautions with respect to the form or insulation of the enclosed parts in order to prevent electrical breakdown to the other parts of the apparatus. Also contained within the hollow conducting member, there are provided means for regulating the filament temperature and the output of the X-ray tube, such means suitably comprising a variable impedance device in circuit with the cathode. One may use, for example, an inductor having an adjustable iron core adapted to vary the effective impedance of the inductor. One desirable arrangement of such an inductor device is indicated in Figs. 2 and 7 in which the inductor is indicated by the numeral 75. An enclosed core (not shown) may be regulated as to position by a mechanism comprising, for example, a pair of bevel gears 78 and a screw drive (also not shown). The regulation of the inductor and, consequently, of the cathode heating current may be accomplished externally of the casing 10 by means of an insulated shaft 79 operable by a handle 80 connecting with the shaft through the wall of the casing. The inclusion of such an irregularly formed mechanism within the walls of the casing would create considerable danger of electrical breakdown except for the advantageous arrangement indicated whereby all the irregular parts are enclosed within the conducting member 30.

The circuit connections for the entire apparatus are indicated schematically in Fig. 8 in which a simplified tube structure has been illustrated for purposes of clarity. In this figure elements corresponding to parts previously described are indicated by identical numerals. Adjustment of the operating voltage is accomplished, for example, by the combination of a variable tap autotransformer 81 and a series resistor 82 connected in circuit with the main transformer primary 18. A voltmeter 83 connected across this primary serves to indicate the prevailing conditions of operation. The transformer secondary 26 is connected between the anode and cathode of the X-ray tube through a suitable current meter 84, which meter may be safely disposed externally

of the casing since all the parts to which it is connected are ground potential. The intermediate electrodes 41 are maintained at desired potentials by connection to spaced points along the transformer secondary 26 as previously indicated.

The focusing cup 38 is maintained at a negative potential with respect to the filament 36 by suitable biasing means connected between them. Such means may comprise, for example, a resistor 86 of relatively high value, say 200,000 ohms, connected in parallel with a condenser 87 having a capacitance on the order of .2 microfarad. Under these conditions, assuming a current flow through the X-ray tube of about 10 milliamperes, a negative bias, which may be about 2,000 volts, will be maintained on the focusing cup due to the relatively high capacity of the condenser 87. This bias will be retained from cycle to cycle since the time constant of the condenser circuit is greater than the duration of a single cycle.

The condenser 87 and the resistance 86 may suitably be enclosed within the hollow conducting member 30 as is indicated in Fig. 7. If desired, the resistance may be also made of adjustable value in which case its regulation may be accomplished externally of the apparatus casing by means corresponding to the regulating means described in connection with the inductor 75.

As a result of the construction described in the foregoing, there is made available a shock-proof and semiportable X-ray apparatus adapted to be operated with a voltage of at least 500,000 volts. The flexibility of the construction is such that it may be moved and manipulated to an extent which makes its use in industrial fields entirely practicable. Thus, the apparatus as a whole may be operated on a factory floor so that the anode arm may be projected inside the various cavities of a metal casting which might itself be too massive to allow convenient manipulation.

While we have illustrated a particular embodiment of the invention, it will be apparent that many modifications may be made by those skilled in the art without departing from the invention. We therefore, aim in the appended claims to cover all such alternative structures as may fall within the true spirit and scope of the foregoing disclosure.

What we claim as new and desire to secure by Letters Patent of the United States is:

1. An electrical discharge apparatus including the combination of a casing enclosing a dielectric medium, a coil immersed in said medium, said coil having one end thereof electrically connected to the casing and its other end appreciably spaced from the casing and adapted to be maintained at a high potential with respect thereto, a hollow conducting member arranged to modify the electrostatic field adjacent the high potential end of the coil and an electrical discharge device at least partially contained within said casing, said discharge device having an anode electrically connected with the casing and a separately heated cathode connecting with the high potential end of said coil within said conducting member, and means also within the conducting member for regulating the heating current to said cathode, said means being adjustable externally of said casing.

2. An electrical discharge apparatus including the combination of a casing enclosing a dielectric medium, a coil immersed in said medium and adapted to develop a high potential difference be-

- between its ends, a hollow conducting member arranged to modify the electrostatic field adjacent one end of the coil, an electrical discharge device at least partially contained within the casing and having a separately heated cathode connecting with the said one end of said coil within said conducting member, said device also including an anode connecting with the other end of said coil, means including an adjustable impedance device enclosed within the conducting member for regulating the heating current to said cathode and means operable externally of said casing for controlling the adjustment of said impedance.
3. A high voltage apparatus including a metal casing containing a dielectric medium, a discharge device at least partially enclosed by the casing and comprising an evacuated envelope enclosing a plurality of electrodes, at least some of said electrodes being within the confines of the casing and being maintained at high potential with respect thereto during the operation of the device, and one or more electrostatic shielding members connected with a corresponding number of said high potential electrodes, each of said members being outside the envelope and interposed between its corresponding electrode and the wall of the casing so as to decrease the radial electrostatic field acting on such electrode.
4. In combination, a metal casing containing a dielectric medium, a discharge device extending at least partially within the casing and comprising an elongated envelope enclosing oppositely disposed discharge electrodes and a plurality of spaced intermediate electrodes, said intermediate electrodes comprising tubular conducting members extending longitudinally of the envelope, means electrically connecting one of said discharge electrodes to the casing, means for energizing the remainder of said electrodes at progressively higher potentials with respect to the casing, and tubular shielding members connected to at least some of the intermediate electrodes, each of said shielding members being arranged outside the envelope so as to surround its corresponding intermediate electrode and being interposed between such electrode and the wall of the casing.
5. A high voltage X-ray apparatus including a metal casing, an X-ray tube within the casing comprising an elongated envelope enclosing an anode, a cathode and a plurality of spaced intermediate electrodes, said anode projecting externally of the casing and being electrically connected thereto, means within the casing for energizing the intermediate electrodes and the cathode at progressively higher potentials with respect to the casing, and electrostatic shielding members electrically connected with at least some of the intermediate electrodes, each of said shielding members being arranged outside the envelope and interposed between the casing and its corresponding electrode.
6. In combination, a metal casing enclosing a dielectric medium, a discharge device extending at least partially within the casing, said device comprising an envelope enclosing oppositely disposed discharge electrodes and a plurality of spaced intermediate electrodes, at least certain ones of said intermediate electrodes being within the confines of the casing, means for maintaining one of said discharge electrodes at a relatively low potential and the remainder of said electrodes at progressively increasing potentials with respect to the casing, and electrostatic shielding members connected to said ones of the intermediate

electrodes, each of said shielding members being arranged outside the envelope and interposed between its corresponding electrode and the inner wall of the casing.

7. In combination, a metal casing, a discharge device within the casing comprising an elongated envelope enclosing oppositely disposed discharge electrodes and a plurality of spaced intermediate electrodes, said device being rotatably mounted with respect to the casing, means for energizing the discharge electrodes at a high potential, electrostatic shielding members outside the envelope interposed between each intermediate electrode and said metal casing, terminals for said intermediate electrodes arranged along the length of the envelope wall, means including sliding contacts co-operating with said terminals for maintaining an electrical connection between each shielding member and its corresponding intermediate electrode during rotation of the discharge device, and means including said sliding contacts for energizing successive ones of said electrodes at progressively higher potentials with respect to the casing.

8. In combination, a metal casing containing an insulating dielectric, a discharge device extending into said casing and comprising an elongated envelope enclosing oppositely disposed discharge electrodes and a plurality of spaced intermediate electrodes, said device being rotatably mounted with respect to the casing, means for energizing the discharge electrodes at high potential, electrostatic shielding members outside the envelope interposed between at least some of the intermediate electrodes and the metal casing, means including a nonrotatable insulating shell positioned between the envelope and the shielding members and supporting the latter, means for maintaining an electrical connection between each shielding member and its corresponding intermediate electrode during rotation of the discharge device, and means connecting with the shielding members for maintaining them at high potential with respect to the casing.

9. An electrical discharge apparatus including the combination of a casing, an energizing means therein having a part thereof electrically connected to the casing and another part at high potential with respect to the casing, a discharge device comprising a portion projecting externally of the casing and a portion projecting internally of the casing, an anode enclosed within the externally projecting portion and electrically connected to the casing, said anode having its active surface at a point relatively remote from the outer wall of the casing, a cathode arranged adjacent to the extremity of the inwardly projecting portion of the discharge device and at a point relatively remote from the inner wall of the casing, means electrically connecting the cathode to the high potential part of said energizing means, a plurality of intermediate electrodes provided in said device between the anode and cathode, all of said intermediate electrodes being within the confines of the casing, and electrical connections for energizing the successive intermediate electrodes at progressively higher potentials with respect to the casing.

10. An electrical discharge apparatus including the combination of a casing, a coil within the casing, said coil being electrically grounded at one end to the casing and having its other end at high potential with respect thereto, a discharge device comprising a portion projecting inwardly of the casing and a portion projecting externally thereof, said device being rotatably mounted on a

- wall of the casing, an anode enclosed within the externally projecting portion of the device and electrically connected to the casing, the anode having its active portion at a point relatively remote from the outer wall of the casing, a cathode arranged adjacent the extremity of the inwardly projecting portion at a point relatively remote from the inner wall of the casing, means electrically connecting said cathode to the high potential end of said coil, a plurality of spaced intermediate electrodes provided in said device between the anode and cathode, all of such electrodes being within the confines of the casing, means providing electrical connection between the intermediate electrodes and correspondingly spaced points along the length of said coil, means accessible externally of the casing for rotating the discharge device, and means for maintaining said electrical connections during rotation of said device.
11. An electrical discharge apparatus including the combination of a casing, a high voltage coil within the casing, said coil having one end thereof insulatingly spaced from the casing and adapted to be maintained at a high potential with respect thereto, a hollow conducting member arranged to modify the electrostatic field between the said high potential end of the coil and the wall of the casing, an electrical discharge device at least partially contained within the casing and comprising an anode and a cathode, and energizing connections between the cathode and the said high potential end of the coil and between the anode and the other end of the coil, the discharge device being so positioned that both the cathode and its energizing connections lie substantially entirely within the confines of the said hollow conducting member.
12. An electrical discharge apparatus including the combination of a metal casing, an X-ray tube lying partially within the confines of the casing, said X-ray tube including an anode and a cathode, a high voltage coil within the casing for energizing the X-ray tube, said coil having one end thereof grounded to the casing and the other end thereof insulatingly spaced from the casing and adapted to be maintained at high potential with respect thereto, means providing electrical connections between the said anode and the casing and between the said cathode and the high potential end of the coil, and a hollow conducting member connected to the high potential end of the coil for modifying the electrostatic field between the same and the wall of the casing, the X-ray tube being so positioned that the anode end thereof projects outwardly through a wall of the casing and that the cathode and its energizing connections lie substantially entirely within the confines of the said hollow conducting member.
13. An electrical discharge apparatus including the combination of a casing enclosing a dielectric medium, a coil immersed in said medium, said coil having one end thereof insulatingly spaced from the casing and adapted to be maintained at high potential with respect thereto, a hollow conducting member arranged to modify the electrostatic field between the said high potential end of the coil and the wall of the casing, an electric discharge device at least partially contained within said casing and comprising cooperating discharge electrodes, said device being energized by connection to the coil, and circuit regulating means enclosed within the said hollow conducting member for controlling the operation of the discharge device, said means being adjustable externally of said casing.
14. An electrical discharge apparatus including a casing enclosing a dielectric medium, a discharge device immersed in said medium, means connected to the terminals of the discharge device for energizing the same, at least one of the terminals of the device being maintained at high potential with respect to the casing by such means, a hollow conducting member of generally smooth contour surrounding the said one terminal and effective to modify the electrostatic field between such terminal and the wall of the casing, and circuit-regulating means enclosed within the said hollow conducting member for controlling the operation of the discharge device, said means being adjustable externally of the casing.
